UNITED STATES PATENT OFFICE.

JOHN WALTER MAY, OF BROOKLINE, MASSACHUSETTS.

PROCESS OF MANUFACTURING SHOES.

1,177,647.

Specification of Letters Patent. Patented Apr. 4, 1916.

Application filed May 13, 1912. Serial No. 696,814.

To all whom it may concern:

Be it known that I, JOHN W. MAY, a citizen of the United States, residing at Brookline, county of Norfolk, State of Massachusetts, have invented an Improvement in Processes of Manufacturing Shoes, of which the following description, in connection with the accompanying drawing, is a specification, like characters on the drawing representing like parts.

In the manufacture of shoes it has heretofore been customary to subject the vamp of the shoe upper to a crimping or forming process in order to give it a shape to fit the last at the base of the instep, but so far as I am aware this crimping process has always been applied to the vamp itself before it is sewed to the tip, quarters, doubler, lining, and other parts forming the complete top of the shoe. The result is that during the process of stitching the vamp to the other parts of the shoe, that is, during the process of stitching the vamp to the tip or to the quarters, and of sewing the lining in place, the vamp is apt to be so distorted that the form or crimp which has previously been put into it will be substantially, if not entirely, removed so that when the shoe is lasted the upper does not fit down against the last at the base of the instep, as it would do if the vamp retained the shape given to it by the crimping process. Moreover, the lining of a shoe is always more or less stiff, due to the fact that it is generally loaded with some stiffening material, and since the vamp is crimped before the lining is attached thereto, the lining does not have the form of the crimped vamp, and, therefore, the non-formed lining acts to prevent the vamp from closely fitting the last as it is designed to do.

It has been proposed heretofore to crimp the lining as well as the vamp, and this has been done by crimping the lining and vamp separately. While this method serves to give the lining a crimped shape, yet it has this disadvantage that when the parts of the shoe are assembled the crimped lining and the crimped vamp are very apt to be displaced slightly relative to each other so as to throw the crimped portions out of proper alinement, and when this condition exists it is very difficult to draw the upper over the last during the lasting operation in such a manner as to obtain a tight fit of the upper against the flat portion of the last.

In order to overcome these difficulties, I propose to perform the crimping operation after the vamp has been sewed to the other parts forming the top of the shoe and when the top of the shoe is completed ready to be lasted. When the crimping is done at this point in the process of manufacture, the lining and the vamp both become subjected simultaneously to the crimping operation and are both properly shaped, and as the next step after the crimping operation is to last the shoe, there is no opportunity for the crimp of the vamp to be lost by manipulating the parts, as is done when the crimped upper is manipulated while it is being sewed to the tip, quarters, etc.

The object of my invention is to provide a novel process of manufacturing shoes which includes this step of crimping the completed upper just prior to the lasting operation.

In order to give a complete understanding of the invention I will describe herein a machine which may be used in the carrying out of my novel process.

In the drawings, Figure 1 is a side view of a crimping device adapted to crimp the completed upper of a shoe; Fig. 2 is an enlarged vertical sectional view through the upper and lower forming tools; Fig. 3 shows a view of a shoe after having been subjected to the crimping operation on my machine; Fig. 4 is a section on the line *a—a*, Fig. 2.

In carrying out my invention the parts of the upper 1 of the shoe, such for instance as the vamp 2, tip 3, quarters 4, lining 5 and doubler 6, are all assembled and sewed together in usual manner, and then after the parts comprising the completed upper are thus secured together and the shoe is ready for the lasting operation the vamp is subjected to a crimping process along the line 7 so as to give to the upper and lining a special shape which approximates that of the last at the base of the instep, so that when the shoe upper is placed over the last and the toe of the upper is drawn around the last during the initial steps of the lasting operation, the crimped portion of the upper will still conform approximately to the flat portion of the last. The result of this condition is that the operator can pull the edges of the upper at the ball of the foot over the last and secure a tight fit of the upper against the top portion of the last with very much less strain than is possible where the

shoe upper is not subjected to the crimping operation.

In the ordinary process of manufacturing shoes it not infrequently happens that in pulling the sides of the upper over the sides of the last the operator is required to apply such an amount of force in order to bring the upper down close against the last as to unduly stretch or strain the leather and to 5 start the stitches which unite the quarters to the vamp, thus injuring the shoe more or less. In thus crimping the upper I find it desirable to soften the parts to be crimped somewhat either prior to or during the 10 crimping operation and this may be done by applying heat to the upper as it is being crimped or applying both heat and moisture. While the desired crimp may be given to the complete upper by any approved means 15 without departing from my invention, I have herein shown a machine which I have designed for this purpose and which I will now describe. The said machine comprises a stand 10 supporting a head 11 which carries a lower crimping tool 12 and an upper crimping tool 13. The lower crimping tool is fixedly secured to the bed and the upper crimping tool is movably mounted in a vertically-moving plunger 14. This plunger 14 20 may be given its vertical movement in any approved way. As herein shown it has extending laterally therefrom a projection 15 which engages an arm 16 of an elbow lever pivoted at 17, the other arm 18 of which 25 lever is connected to an arm 19. The arm 16 of the lever is connected by a link 20 to a treadle 21 of suitable construction.

The arm 19 is pivotally connected at its forward end to the upper end of a link 23, 30 the lower end of which is pivoted to the head at 24. This arm 19 carries a finger 25 which is pivotally connected thereto at 26, and the end of which is connected to a rod 27 that extends up through the arm 19 and is acted 35 upon by a spring 28. A spring 29 connecting the pivotal point 17 with the arm 19 serves to hold the parts normally in the position shown in Fig. 1.

When the treadle 21 is depressed the arm 50 16 is moved downwardly, thus permitting the plunger to fall by gravity, and the turning movement of the elbow lever 16, 18 carries the finger 25 over a roll 30 mounted in the upper end of the plunger 14 and further continued downward movement of the 55 treadle results in applying pressure to the plunger through the arm 19 and finger 25. When the treadle is released the spring 29 restores the parts to their normal position. 60 This particular way of operating the plunger 14 does not form any part of my invention, and the plunger might be operated by other means without departing from the invention.

65 The forming tools 12 and 13 are of special

shape adapted to give the vamp the desired crimp or form. The upper forming tool 13 is provided on its under face with a V-shaped groove 31 which is curved in the direction of its length, as seen best in Fig. 4, 70 said groove having the low portion 32 and the high portion 33. The lower forming tool is provided with a V-shaped extension 34 adapted to fit the groove 31, that is, said extension is provided with the side faces 35 75 adapted to engage the faces of the groove 31, and this extension is curved in the direction of its length to conform to the curvature 32, 33 of the groove.

In using the device the completed shoe 80 upper is placed on the lower forming tool, as shown in Figs. 2 and 4, and the upper tool is then depressed to bring it into operative engagement with the vamp, and the pressure is applied to the upper tool to secure the crimping operation.

As stated above I find it desirable to soften the lining during the crimping operation because in most shoes the lining is comparatively stiff and the crimping of the 90 lining in a dry state would be liable to cause it to break. My novel process, therefore, includes this step of softening the lining during the crimping operation, and this may conveniently be done by applying moisture 95 and heat to the lining. I also find that it is desirable to apply heat to the upper during the crimping operation so as to produce a more permanent set to the crimping. In the machine herein shown the softening of 100 the lining during the crimping operation is provided for by forcing moist or saturated steam against the underside of the lining, and in order to permit this to be done, I propose to make the lower tool 12 hollow, 105 as seen in Fig. 2, and provide it with an open groove or slot 36 extending along the apex of the extension, and further to provide means for delivering saturated steam vapor through opening 36. The head 11 is 110 shown as provided with a chamber 37 adapted to contain water, and this chamber is covered by a cap or plate 38 having an opening 39 and to which the lower tool 12 is fixedly secured by means of a clamping ring 115 40, said tool having the flange 41 thereon to be engaged by the ring. The chamber 37 is adapted to contain water up to about the level of the line 43, and I have provided a device for delivering steam and air mixed 120 into the chamber 37 against the surface of the water therein. The air which is mixed with the steam causes it to condense more or less, thus making a saturated vapor which is somewhat in the nature of a fog, and this 125 moist or saturated condition of the vapor is augmented by the presence of the water in the chamber 37. The means for delivering the steam and air to the chamber comprises a nozzle member 44 to which a steam pipe 130

45 is connected and which is provided with a nozzle 46 having a comparatively small opening and leading into a tube 47 which is secured to the member 44 and extends up 5 through the body of liquid in the chamber 37.

48 is a deflector situated at the upper end of the tube 47 and adapted to deflect the steam and air downwardly against the body of water. The member 44 is provided with 10 air inlet ports 50 situated at the base of the nozzle 46, and with this construction the force of the steam issuing from the nozzle 46 will draw air in through the ports 50, and this air mixing with the steam will cause 15 more or less of it to condense, thus producing the saturated steam vapor in the chamber 37. The deflection of the steam and air down against the body of water 43 also causes further condensation and further 20 saturation of the vapor so that the vapor which is delivered through the opening 36 is extremely wet and highly adapted for moistening and softening the lining of the 25 vamp at the point where the crimping occurs. If desired, I may provide apertures through the walls 35 of the extension 34 so that the moistening vapor will be delivered not only along the apex of said extension, but through the sides thereof. The condensation 30 of the steam causes an accumulation of water in the chamber 37 and the surplus water will overflow into the pipe 47 through the ports 50 into an annular groove 51, from which it drains into the waste pipe 53 35 through the drain port 52.

In the operation of the device the completed shoe upper is placed over the lower tool 12 with the lining against the extension 34 of said tool and the upper tool is then 40 forced against the shoe upper, as seen in Figs. 2 and 4. The saturated steam vapor issuing from the slot 36 moistens the lining so that it can be shaped or formed over the extension 34 without danger of breaking or 45 cracking, and the upper and lower tools co-operate to force the shoe upper into the desired shape.

The extension 34 and the groove 31 are of a shape in the direction of their length to 50 give the upper of the shoe the desired contour at the base of the instep, so that when the shoe is placed over the last the vamp will approximately fit the top of the last even when the toe of the shoe is drawn over 55 the toe of the last in initial steps of the lasting operation. As a result when the sides of the vamp are pulled over the sides of the last, the crimped portion of the vamp will lie down closely against the top of the last 60 with a tight fit, and this desired tight fit can be secured without subjecting the upper to any undue strain which is likely to injure it or loosen the fittings. Moreover, with my invention it is possible to economize some- 65 what in the leather used in cutting the vamp,

for the crimping operation gives the vamp a shape to approximately fit the last before the lasting operation, and in order to secure a tight fit of the upper against the last it is not necessary to pull so great an extent of 70 the upper over the edge of the last as is necessary with the old method.

It will be noted that the apex of the extension 34 of the tool 12 is flattened somewhat so that when the tools are placed in 75 co-operative relation a space will exist between the bottom of the groove 31 and the apex of the extension 34. The purpose of this is to allow a comparatively free space over the slot 36 for the moist vapor to work 80 out and penetrate through the pores of the lining, doubler and vamp, thus to facilitate the softening operation. If this space 31 did not exist the passage of the steam into and through these parts would be choked 85 and prevented.

The upper crimping tool can be heated in any suitable way, and as herein shown it is provided with openings 62 into which an electric heating element 65 may be inserted, 90 this element being controlled by a suitable switch 66. The upper tool is removably mounted in the plunger, said tool being provided with a stem 63 inserted into an opening in the bottom of the plunger and held in place by a removable pin 64. The lower tool is also removably held in place by the collar 40. By making the tools removable it is possible to use tools of any shape or 95 size, depending upon the shape which it is desired to give to the upper and the area of the upper which it is desired to subject to the crimping or molding operation. In the particular machine which I have herein chosen to illustrate as an aid in giving an 100 understanding of my invention, the molding tools are of a size to act on a limited portion of the upper, but as I believe it is new with me to crimp or mold the portion of the shoe upper at the base of the instep to approximately the shape of the last just prior to the 105 lasting operation, I desire to claim this feature broadly, whether a greater or a less portion of the shoe upper is subjected to the 110 molding operation.

Having fully described my invention, what I claim as new and desire to secure by Letters Patent is:—

1. The process of making shoes which consists in assembling and securing together the vamp, tip, lining and other parts going to make up a shoe upper, molding the portion of said upper at the base of the instep to the shape of the last and then lasting the upper. 120

2. The process of making shoes which consists in assembling and securing together the vamp, tip, lining and other parts going to make up a complete shoe upper, subjecting the vamp and lining at the base of the instep to a crimping operation, and direct- 125 13.

ing a heated moistening vapor against the lining at the point where the crimping operation is being performed and during such operation and then lasting the crimped upper.

3. The process of making shoes which consists in assembling and securing together the vamp, tip, lining and other parts going to make up a complete shoe upper, subjecting the portion of the vamp and lining at the base of the instep to the action of complemental molding tools in such manner as to crimp the same, and then lasting the upper.

15 4. The process of making shoes which consists in assembling and securing together

the vamp, tip, lining and other parts going to make up a complete shoe upper, subjecting the portion of the vamp and lining at the base of the instep to a crimping operation and simultaneously moistening and softening the portion of the lining which is being crimped and then lasting the crimped upper.

20 In testimony whereof, I have signed my name to this specification in the presence of two subscribing witnesses.
